UNITED STATES PATENT OFFICE.

SIDNEY H. SHORT, OF CLEVELAND, OHIO.

COMBINED GAS AND ELECTRIC GENERATOR PLANT.

SPECIFICATION forming part of Letters Patent No. 594,435, dated November 30, 1897.

Application filed May 4, 1896. Serial No. 690,221. (No model.)

To all whom it may concern:

Be it known that I, SIDNEY H. SHORT, a citizen of the United States, residing at Cleveland, in the county of Cuyahoga and State of Ohio, have invented a new and useful Combined Gas and Electric Generation Plant, of which the following is a specification.

This invention relates to a combined gas and electric generation plant.

In my application, Serial No. 586,798, I have set forth and described an invention in method of and means for electric generation, wherein carbon, coal, or carbonaceous material is subjected to the action of an electrolyte which is capable of receiving oxygen and transferring the same electrochemically to the carbon, coal, or carbonaceous material to effect an oxidation thereof, such action resulting in the generation of an electric current. I have conceived that this method of electric generation may be most economically and efficiently carried into practical commercial effect in connection and conjunction with a gas-generating plant, and this conception forms the basis for the present invention.

The invention, therefore, consists, substantially, in the construction, arrangement, location, combination, and method of operation, all as will be more fully hereinafter set forth, shown in the accompanying drawings, and finally specifically pointed out in the appended claims.

In the drawings, Figure 1 shows an illustrative form of apparatus adapted for the purposes of my invention. Fig. 2 is an enlarged broken sectional detail view of the coke-holder.

In the drawings reference-sign A designates a suitable gas-retort adapted to receive the coal, and wherein said coal is baked to evolve therefrom the gases, the evolved gases passing off in the usual manner in gas plants through a suitable connection B to a purifier C, which may be of the usual or any suitable construction and arrangement, thence through connection D to the service-main F or to the reservoir G, or to both, in the usual or any convenient manner.

H designates the furnace for supplying the requisite heat for baking the coal, which is introduced into the retort A. The coal may be introduced into the retort A in any suit-

able or convenient manner. In practice, however, I prefer to employ an arrangement wherein the coal may be readily fed into the retort A. I have shown an illustrative form of apparatus embodying this idea wherein a hopper J is adapted to receive the coal previous to its being fed into the retort, said hopper opening at its lower end into the retort and provided with a suitable cover K at the top thereof, which cover is made removable, but which is gas-tight when secured in its closed position. A plunger L, having a pusher end M, is arranged to travel adjacent to the lower end of the hopper J, and when actuated is adapted to feed or push the coal into the retort. The plunger or arm L may be actuated in any convenient or desirable manner, by hand or machinery—for instance, by means of a crank connection with a disk N, which may be rotated in any suitable manner. In order that any gas evolved from the coal in the retort may not escape through the hopper J, it may be desirable to open communication between said hopper and the connection B, as indicated at O.

The parts so far described may be of any usual, convenient, or ordinary construction of gas plant, and I desire it to be understood that my invention is not limited to the specific construction, location, or details of arrangement thereof.

In my said prior application I have described that the process of generating electricity by subjecting the carbon to the electrochemical action of an electrolyte capable of receiving oxygen and of transferring the same to the carbon to effect an oxidation thereof is best effected under the influence of heat, the electrolyte being maintained, preferably, in a molten condition, and better results being obtained when the apparatus is heated. In the present invention, therefore, I arrange the carbon-holder P, which forms the positive element of the cell, but the negative pole of the couple, adjacent to and in connection with the gas-retort A, and preferably at the farther end thereof with reference to the hopper J, in order that the residue from the gas-retort, after all the gas for illuminating or other purposes has been baked out of or evolved from the original coal, thereby leaving the same in the form of coke, may be

pushed by the plunger L and its plunger-rod M and the fresh coal from the retort into the carbon-holder of the electric generating plant while still in its heated condition, it being understood that when the carbon is maintained in a heated condition the nascent oxygen of the electrolyte or resulting from the electrochemical action of the electrolyte will attack the carbon more vigorously and freely, and hence result in a more efficient electric generation. Therefore in the present invention as fast as new coal is supplied to the gas-retort to produce illuminating or heating gas the previously exhausted—that is, the coke product, which the new or fresh coal replaces—is fed into the electric generating apparatus or carbon-holder P while still in its heated condition, and is therefore consumed or oxidized in the process of electric generation, as described in said prior application, by the electrochemical action of the electrolyte Q. The carbon-holder P should be of suitable conducting material and of such a nature as not to be acted upon by the electrolyte. I have found iron to be a suitable material for this purpose, and the said holder P should be so constructed as to permit the electrolyte to gain access to the carbon contained therein. This can be effected by suitably perforating the bottom of said holder. The necessary oxygen which is required to effect an oxidation of the carbon or coke in the holder P is supplied to the electrolyte in any suitable or convenient manner. In the form of apparatus shown I provide an air-pump R for forcing a current of air through connection S into the negative element T of the cell, and from which, through electrochemical action, the oxygen is transferred through the electrolyte Q to the coke contained in the holder P, where it attacks and oxidizes such coke, the products of such oxidation passing off in the form of gases, and the result of such oxidation is the production of a current of electricity, the positive pole of the couple being connected electrically to the negative element T, as indicated at V.

As described in my prior application, the negative element T is composed of an oxidized or oxidizable material—such, for instance, as lead.

A convenient method of maintaining the negative element T of the cell and the electrolyte Q and the coke contained in the holder P at the required degree of temperature to secure the best possible results and in the most efficient and economical manner, the products of combustion from the furnace II, after performing the work of baking the coal in retort A, pass through connection W to the vessel A', into which the negative element of the cell and the electrolyte Q are contained, and maintains the same at the proper or required degree of temperature.

The coke-holder is of suitable conducting material—say, for instance, iron—and the electrolyte may gain access to the coke con-

tained in said holder through suitable perforations (indicated at A²) in the bottom thereof, or, if desired, and as clearly shown in Figs. 1 and 2, the bottom part of said holder may comprise the portion C² of suitable porous material, through which the electrolyte may pass, as will be clearly understood.

It will be understood that the coke-holder P of the electric generation plant should be suitably insulated, as indicated at B', from the gas-retort A in order to prevent short-circuiting of the current generated.

It will be understood, of course, that, if required, several electric generation-cells may be employed in connection with each gas-retort should it be found that one such cell will not consume or utilize continuously the coke product of such retort.

From the foregoing description it will be seen that I combine a gas-generating plant with an electric generating plant wherein the gas generated may be utilized for any purpose for which the gas is adapted, and the electric current generated may in similar manner be utilized for any purpose for which it is adapted. It will also be seen that I reduce the cost of electric generation to the lowest possible point by utilizing the coke while in its heated condition for the electric generation and by utilizing the heat products required for the gas generation to maintain the electric generation cell or cells at the required degree of temperature for the most effective results.

It will be understood that the principles of my invention may be embodied and carried out in a wide variety of specific forms and arrangement of apparatus without departing from the spirit or scope of my invention. I do not desire, therefore, to be limited or restricted to the forms of apparatus shown and described; but,

Having now stated the object and nature of my invention and an operative form of apparatus embodying the same, and having explained the purpose, function, and mode of operation thereof, what I claim as new and useful and of my own invention, and desire to secure by Letters Patent of the United States, is—

1. In a combined gas and electric generation plant, a gas-retort, means for heating the same, a coke-holder adapted to receive the coke from said retort, a material electronegative with respect to such coke, an electrolyte intervening between said electronegative material and the coke, means for supplying oxygen to said electrolyte through said electronegative material, and means whereby the electrolyte and the electronegative material are heated by the products of combustion of said retort-heating means, as and for the purpose set forth.

2. In a combined gas and electric generation plant, a gas-retort, means for heating the same, a coke-holder communicating with but insulated from said retort, an electrolyte in

which said carbon-holder is immersed, a material electronegative with respect to the coke, and means for heating the said electronegative material and electrolyte by the products of combustion of said retort-heating means, as and for the purpose set forth.

3. In a combined gas and electric generation plant, a gas-retort, means for heating the same, means arranged to receive the coke product, therefrom while in its heated condition, a lead electrode, an electrolyte in which said electrode and also said coke are immersed, means for subjecting said electrolyte to the

action of the products of combustion of the gas-retort-heating means, whereby said electrolyte is maintained in a heated condition, and means for supplying oxygen to said electrolyte through said lead electrode, as and for the purpose set forth. 15

In witness whereof I have hereunto set my 20 hand this 27th day of April, 1896.

SIDNEY H. SHORT.
